Oleg Cassini, New York, N. Y.

Application June 11, 1954, Serial No. 30,944

Term of patent 3½ years

(Cl. D3—26)

To all whom it may concern:

Be it known that I, Oleg Cassini, a citizen of the United States of America, residing in New York city, county of New York, and State of New York, have invented a new, original, and ornamental Design for a Dress or Similar Article, of which the following is a specification, reference being had to the accompanying drawing, forming part thereof.

Fig. 1 is a front view of a dress or similar article showing my new design.

Fig. 2 is a rear view thereof on a reduced scale.

I claim:

The ornamental design for a dress or similar article, substantially as shown.
